(57) **CLAIM**

The ornamental design for a display screen or portion thereof with animated graphical user interface, as shown and described.

DESCRIPTION

FIG. 1 is a front view of a first embodiment showing a first image in a sequence of a display screen or portion thereof with animated graphical user interface;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof; and,

FIG. 7 is a front view of a seventh image thereof.

The appearance of the animated graphical user interface sequentially transitions between the images shown in FIGS. 1-7. The process or period in which an image transitions to another image forms no part of the claimed design.

The outer line showing of a device is for the purpose of illustrating environmental structure and forms no part of the claimed design. All other broken line showing of the display screen or portion thereof with animated graphical user interface is for the purpose of illustrating portions of the article and forms no part of the claimed design.
